DESIGN FOR A DRILLING MACHINE

Lawrence L. Schauer, Wyoming, Ohio, assignor to
The Cincinnati Bickford Tool Company, Cincinnati,
Ohio, a corporation of Ohio

Application June 21, 1940, Serial No. 93,174

Term of patent 14 years

To all whom it may concern:

Be it known that I, Lawrence L. Schauer, a citizen of the United States, residing at Wyoming, in the county of Hamilton and State of Ohio, have invented a new, original, and ornamental Design for a Drilling Machine, of which the following is a specification, reference being had to the accompanying drawings, forming part thereof.

Figure 1 is a perspective view of a drilling machine showing my new design.

Figure 2 is a rear elevational view of the drilling machine shown in Figure 1.

I claim:

The ornamental design for a drilling machine, substantially as shown.

LAWRENCE L. SCHAUER.
